UNITED STATES PATENT OFFICE.

REINHOLD HERMAN, OF CRAFTON, PENNSYLVANIA.

DESIGN FOR A BRACKET FOR ELECTRIC WIRES.

SPECIFICATION forming part of Design No. 19,241, dated July 30, 1889.

Application filed June 7, 1889. Serial No. 313,505. Term of patent 14 years.

To all whom it may concern:

Be it known that I, REINHOLD HERMAN, a citizen of the United States, residing at Crafton, in the county of Allegheny and State of Pennsylvania, have invented and produced a certain new and original Design for Brackets for Electric Wires, of which the following is a specification.

The invention described herein relates to a certain new and original design for brackets for electric wires.

In the accompanying drawings, forming a part of this specification, Figure 1 is a view in elevation of a bracket embodying my invention. Fig. 2 is a sectional view on the line $\alpha\alpha$, Fig. 1.

An arm 2, consisting of radially-arranged ribs or webs 3, extends from a base-plate 1, having notches or slots 4 in two of its opposite edges. Around the outer end of the arm is a spiral rib 5.

In Fig. 2 is shown a modified form of the bracket, in which the outer portion 4 of the arm is turned to an angle with the main portion thereof.

The leading or characteristic features of my design are a base-plate notched as regards its edges and an arm star-shaped in cross-section, whose outer end may be angularly arranged, extending from the base-plate.

30

I claim herein as my invention—

The design for brackets for electric wires, as herein shown and described.

In testimony whereof I have hereunto set my hand.

REINHOLD HERMAN.
